UNITED STATES PATENT OFFICE

128,791

DESIGN FOR A COMBINED DESK AND COUNTER OR SIMILAR ARTICLE

Ohmer Ullery, Columbus, Ohio, assignor to The Ohio Fuel Gas Company, Columbus, Ohio, a corporation of Ohio

Application January 24, 1941, Serial No. 98,370

Term of patent 14 years

To all whom it may concern:

Be it known that I, Ohmer Ullery, a citizen of the United States, residing at Columbus, in the county of Franklin and State of Ohio, have invented a new, original and ornamental Design for a Combined Desk and Counter or Similar Article, of which the following is the specification, reference being had to the accompanying drawing, forming a part thereof.

Figure 1 is a front perspective view of the combined desk and counter or similar article,
showing my new design.

bined desk and counter or similar article.

The characteristic features of my design are shown in full lines on the drawing.

I claim:

The ornamental design for a combined desk
and counter or similar article, substantially as shown and described.

OHMER ULLERY.
